(57) **CLAIM**

We claim the ornamental design for a portion of a roller
skate, as shown and described.

DESCRIPTION

FIG. 1 is a perspective view of a roller skate, seen from the
front and right sides thereof, showing our new design;
FIG. 2 is a right side view thereof;
FIG. 3 is a left side view thereof; and,
FIG. 4 is a front end view thereof.

The broken line showing of other parts of the roller skate
shown in the drawing is for illustrative purposes only and
forms no part of the claimed design.
